UNITED STATES PATENT OFFICE.

CHESTER H. DRESSER, OF NEW YORK, N. Y.

CORKING AND FILLING MACHINE.

SPECIFICATION forming part of Letters Patent No. 312,448, dated February 17, 1885.

Application filed April 21, 1884. (No model.)

To all whom it may concern:

Be it known that I, CHESTER H. DRESSER, of the city, county, and State of New York, have invented a new and useful Improvement 5 in Bottling-Machines; and I do hereby declare that the following is a full and exact description thereof, reference being had to the accompanying drawings, and to the letters of reference marked thereon, making a part of this specification.

My invention relates more especially to that class of machines which are adapted to the bottling of mineral waters or other liquids under pressure, and has for its object to facilitate, by simple and effective automatic mechanism, as hereinafter fully described, a feed of sirup to the aerated liquid, a supply 15 of corks to the filling-cylinder, the introduction and forcing of the cork into the bottle when filled, and the delivery of the bottle 20 when filled and corked in position for ready removal.

In the accompanying drawings, Figure 1 is an elevation in perspective of my improved 25 bottling and corking machine; Fig. 2, a horizontal section through the same between its horizontal operating-shaft and rotating table; Fig. 3, a diagram view illustrating the cam and connections for rotating the table, and the locking device for the same; Fig. 4, a diagram 30 illustrating the cam and the rack-and-pinion movement for operating the corking-plunger. Fig. 5 illustrates the cam and its connections for operating the sirup-valve. Fig. 6 illustrates the cam and its connections 35 for raising the bottles. Fig. 7 illustrates the cam and its connections for locking the bottle in its raised position; Fig. 8, an enlarged view of the cork-feeding jaws; Fig. 9, a detached view, partly in section, of the cork-hopper and delivering devices for the same, 40 and Fig. 10 the double cam and connections for operating the cork-feeding jaws.

A represents the filling-cylinder; B, the 45 sirup cup or gage, supplied through a tube, B; C, the feed-tube supplying the liquid under pressure from the reservoir to the sirup-gage, from which it is led through the pipe C to the filling-cylinder, and D the escape-valve and 50 tube connected with the filling-cylinder. These parts may be of the same construction and be arranged and supported upon a frame,

E E, in like manner as in the bottling-machines now in use.

A plate or table, F, is fitted to rotate within 55 the top of the frame, under the filling-cylinder A, and is provided with four receptacles, G G G G, placed at equal distances apart, and which are secured in the table so as to project below it.

Within each receptacle G a cylindrical case or cup, G', is fitted, (see Figs. 1 and 6,) so as to rest upon the bottom of the receptacle and project above the table, and within the case two or more springs, a a, are secured, so as 60 to clasp and center the bottle within the case. The case serves not only to hold the bottle, but as a guard in the event of the bursting of a bottle in filling. The rotating table F is mounted upon the end of a vertical spindle, 70 F', which is stepped in a cross-beam of the frame E E. An intermittent rotation of the shaft is produced by means of a loose collar and disk, H, fitted upon the spindle F', (see Fig. 3,) to turn freely thereon, and which is 75 made to reciprocate one-quarter of a revolution back and forth by means of an arm, H', (see Fig. 3,) pivoted thereto, and which projects from a frame, H², embracing a cam, H³, fitted upon a counter shaft, J⁴, mounted to revolve in the frame parallel with the driving-shaft of the machine, to which it is geared by a pinion, K, on the driving-shaft, gearing into a spur-wheel, K', on said counter-shaft, as shown in Fig. 1. At each movement of the 80 disk H the shaft F is made to rotate one-quarter of a turn by the engagement of a lug or finger, H⁴, fixed to the spindle F', and which, projecting radially therefrom, is engaged by one of four notches, c, cut on the 85 under face of the disk. At each movement of the spindle F' and of the table F, mounted thereon, the bottle, clasped and centered within the case G' in one of the receptacles G, is brought immediately under the filling-cylinder A. 90

When the table is so turned as to bring the bottle in position for the foregoing movements, it is rigidly held in such position by means of a latch or bolt, R, (see Fig. 3,) adapted to 100 work loosely through the frame E of the machine, so that its inner end may engage a notch formed in the periphery of the revolving table F, in which position it is held by

means of a spring, R' , whose free end is slotted to embrace an annular groove in the outer end of the bolt. The bolt or latch R is withdrawn from the table, so as to allow its partial 5 rotation, by means of a curved lever, R^2 , pivoted to the frame E , so as to form a lever of the first class, with one end bearing against the inner side of the spring R' and its other end in position to be engaged and pressed upon by a 10 pin, R^3 , projecting laterally from the cam H^3 , which serves to rotate the table. The adjustment is so made as that the pin R^3 will bear upon the lever R^2 , and by swinging the same upon its pivotal point will force outward the 15 spring R' and withdraw the bolt R , so as to free the revolving table before the cam H^3 begins to act upon the frame H^2 and will hold the bolt in its withdrawn position until the notch in the edge of the revolving table has 20 moved out of register with said bolt R . During the rotary movement of the table F , by which one bottle is withdrawn and another brought into place beneath the filling-cylinder, the valve of the sirup cup or gage B is tripped, to 25 allow a supply of sirup to enter the gage from the supply-tube B' , by means of a tripping-lever, T , pivoted at one end to the frame E , so that its opposite end may strike the valve-stem. This lever T is actuated by a vertical 30 rod, T' , extending from the tripping-lever to the free end of a lever, T^2 , pivoted at its opposite end to the frame beneath, so as to extend over a cam, J^3 , upon a disk fitted on the counter-shaft J^4 . The charge of sirup admitted 35 into the gage B is prevented from flowing back into the liquid-supply pipe C by means of a check-valve therein, which is forced open by the pressure of the liquid admitted thereto when the valve in the supply-pipe is opened 40 by an attendant. So soon as the bottle is brought by the rotation of the table F into place immediately under the filling-cylinder A , the neck of the bottle is forced up into the rubber-lined opening of the cylinder (which 45 is adapted to encircle and form a close watertight joint with the neck) by means of a plunger, L , (see Fig. 6,) fitted under the table F in line with the filling-cylinder, in position to enter an opening in the bottom of the receptacle G , so as to bear against the case G' and 50 force it and the bottle contained therein up toward the cylinder. The plunger is secured upon the end of a rod, L' , to which is hinged the inner end of a lever, L^2 , pivoted centrally 55 to an upright, E^2 , of the frame E , and which carries upon its outer end an adjustable weight, L^3 . The lower end of the rod L' is also connected by the rod L^6 to the outer end of a lever, L^4 , whose inner end is pivoted to a bracket 60 dependent from the frame E , its outer end being prolonged beyond the end of the rod L' , so as to be borne down upon and actuated by a cam, L^5 , on the counter-shaft J^4 . The surface of the cam L^5 is so extended (see Fig. 6) and its position on the shaft so adjusted with reference to the lever L^4 as that the latter will be held down during the partial rota-

tion of the table F ; but so soon as this movement ceases and a bottle has been brought thereby into register with the filling-cylinder 70 A the end of the lever L^4 is released by the cam, and the weight L^3 is left free to force up the plunger L , and with it the case G' within the receptacle G , with sufficient power to carry the neck of the contained bottle up into the 75 filling-cylinder. The supply-cock in the filling-tube C is opened by hand by a movement of the lever C' , (see Fig. 1,) and is held open until the bottle is filled, and then closed again. While the bottle is thus being filled the movement of the plunger L is prevented, and it is 80 automatically locked by means of a catch, M , (see Fig. 7,) adapted to engage the plunger, and which is thrown into contact therewith so soon as the plunger is elevated by means of a 85 lever, M' , actuated by a rod, M^2 , whose lower end is connected to a second lever, M^3 , actuated by a cam, M^4 , on the counter-shaft J^3 . At the proper interval predetermined as sufficient to allow the bottle to be filled from the 90 cylinder the continued rotation of the cam M^4 releases the locking device, and the continued rotation of the cam L^5 leaves the plunger L free to descend clear of the case holding the bottle, so that the following movement of the 95 ratchet-disk H , actuating the spindle F' , may operate to carry the filled bottle away from the cylinder and bring the next into line therewith. 100 A cork carrying device consisting of a pair of reciprocating jaws, N N' , pivoted together and fitted to move back and forth upon a plate, N' , (see Fig. 8,) and which are closed together as they move outwardly by springs N^2 N^2' , inserted to bear outwardly against their inner 105 ends, and are opened as they are drawn back by the engagement of said ends with inwardly-converging ribs or flanges N^3 N^3' , is fitted under the end of a tube, N^4 , leading upward to a hopper or receptacle for the corks, N^5 . 110 When the jaws are drawn back upon the plate N' and opened, they are brought into register with the mouth or lower end of the tube N^4 , (see Fig. 1,) so that a cork dropping through the tube will be discharged between the jaws, 115 with its lower end resting upon the bottom of the case. When the jaws are pushed outwardly, they will in their movement close upon the cork, and thus hold it, and with the cork in their embrace are carried into line immediately over the top of the filling-cylinder 120 A . At this moment a plunger, P , upon the lower end of a bar, P' , which is mounted to reciprocate vertically over the cylinder in suitable bearings upon a standard, E^3 , of the 125 frame, is made to descend and push the cork out from between the jaws into an opening in the top of the cylinder, and, resting upon it, hold it there until the bottle beneath is filled, the jaws being in the meantime drawn back, 130 their springs allowing them to spread and separate from the plunger as they are drawn back. So soon as the bottle is filled a further downward movement is imparted to the plun-

ger P sufficient to cause it to drive the cork through the filling-cylinder into the neck of the bottle before the latter is withdrawn from the cylinder. The plunger is thereupon with- 5 drawn up into its first position. These movements of the plunger P are produced by means of a rack on the upper end of the plunger-bar P', engaged by a pinion, P², mounted in bearings in the standard E³ of the frame, 10 said pinion being actuated by a second reciprocating rack-bar, P³, on the opposite side of the standard, (see Fig. 4,) which is hinged at its lower end to the outer end of a pivoted lever, P⁴, pivoted at its inner end to the frame 15 in position to extend out over the counter-shaft J⁴ at a right angle thereto and be engaged by a cam, P⁵, on said shaft. This cam P⁵ is so fashioned as that it will in its rotation first carry up the bar P³ at the appropriate 20 moment far enough to cause the plunger P, geared thereto, to move down to push the cork into the cylinder; next hold the bar in its elevated position for a given interval of time; then force it up quickly and powerfully, 25 so as to cause the plunger P to force the cork into the bottle, and finally release the bar P³ entirely, so as to allow it to drop to its full extent, and thereby elevate the plunger P to its first position. The drop or downward 30 movement of the bar P³ is insured positively by means of a toe or wiper, P⁶, fitted on the side of the cam, and adapted to engage an arm, P⁷, pivoted under the lever P⁴, parallel therewith and connected thereto by a link, 35 P⁸, as fully illustrated in Fig. 4. The bar P³ is hinged in its length to facilitate its free movement. A friction-roller, r, is fitted to the lever P⁴, against which the cam P⁵ is made to bear to facilitate its movement. The re- 40 ciprocating movement of the cork-clamping jaws N N upon the plate N' is effected by means of a double cam, S¹, upon the shaft J⁴, (see Fig. 10,) which is made to operate, as hereinbefore described, upon a lever, S', pivoted at one end 45 to the frame E, and connected at its outer end by means of a coupling-rod, S², with a bell-crank, S³, (see Fig. 1,) whose outer end is coupled to a sliding bar, S⁷, to which the jaws N N are pivoted, as shown by the dotted lines 50 in Fig. 8, so that the motion derived from the shaft J⁴ through the cams S¹ is imparted to said jaws N. The rotary movement of the shaft J⁴ is made to oscillate the lever S' by means of a ring, S⁸, included in the length of the lever, 55 and adapted to encircle the cam upon the shaft J⁴, so that the two projecting surfaces S⁴ S⁵ of said cam will in revolving pass the one on the one side and the other on the opposite side of said ring, to engage laterally-projecting in- 60 clined flanges S⁶ S⁷, formed one on each face of the ring, and the vibration of the end of the lever up and down will, by rocking the bell-crank S³, produce the desired reciprocation of the arm S⁷, carrying the cork-clamping jaws. 65 The corks are supplied to the jaws N N through a tube, N⁴, from a hopper or reservoir, N⁵, attached to the standard E of the frame of the

machine. The corks are placed loosely in this hopper, and they are brought one at a time in a vertical position over the upper 70 end of the tube N⁴ by means of a frame or disk, N⁶, (see Fig. 9.) adapted to revolve in the lower part of the hopper, and which is pierced with a series of perforations, n, whose upper ends are conically enlarged. These 75 perforations are so located as that a rotation of the disk will bring each of them in succession over the tube N⁴. The conical cavities at the upper end of each opening will, in moving beneath the loose corks, each select 80 one, and the cork will thus be carried within the recess until it reaches a vertical position over the mouth of the tube N⁴, when the cork will drop into said tube. The rotation of the disk N⁶ is produced by means of a swinging 85 lever, n', (see Fig. 9.) pivoted at one end to the bottom of the hopper N⁵, to swing back and forth under the same, and which, engaging downwardly-projecting teeth upon a ratchet-wheel, n², fixed to the disk N⁶ by an 90 axle or spindle extending through the bottom of the hopper, will rotate said disk N⁶. The notches in the ratchet-wheel n² are placed at such intervals as that each movement will serve to bring one of the openings in the disk 95 N⁶ over the delivery-tube N⁴. The swinging movement of the lever n' is derived from the movement of the reciprocating bar P³, mounted to move vertically over the filling-cylinder in suitable bearings upon the standard E³ of 100 the frame, as hereinbefore described. The movement of the bar P³ is communicated to the lever n' by means of two pins, n³ n⁴, projecting from the face of the bar in position to strike the long projecting arm of a bell-crank 105 lever, n⁴, pivoted to the frame E³, and whose shorter arm is coupled by means of an interposed link, n⁵, with the outer end of the arm n'. 110

I claim as my invention—

1. In a bottling-machine, the combination, 110 with its feeding-tubes and filling-cylinder, and with an intermittently-rotating table adapted to bring the bottles to be filled into position beneath said cylinder, of receptacles formed in the table, cases fitted in said receptacles to move vertically therein and receive the bottles, spring-clamps within each case to center the bottles therein, and a reciprocating plunger adapted to play through the bottom of the receptacle and force upward the bottle-case and 115 bottle when the latter is in position beneath the filling-cylinder, substantially in the manner and for the purpose herein set forth.
2. In a bottling-machine, the combination, 120 with its master-shaft J⁴, and with a table 125 mounted to rotate upon a vertical spindle under its filling cylinder, of a cam upon the master-shaft, embraced by a forked lever so pivoted as to be oscillated by the rotation of the cam, a disk mounted to rotate loosely back and forth upon the spindle, a coupling-bar connecting the outer arm of the oscillating lever with the disk, to produce its reciprocation, and a lug upon the spindle adapted to 130

engage notches on the loose disk, so that the reciprocating movement of the disk shall produce an intermittent movement of the spindle, all substantially in the manner and for the purpose herein set forth.

3. In a bottling-machine, the combination, with its intermittently-rotating table F, and with the frame encircling said table, the spindle upon which the table is mounted, and the oscillating lever H, by which the spindle is actuated, of a lever, R², pivoted to a bracket on the frame in position to be tripped by the movement of the cam actuating the oscillating lever H², and to engage and thereby unlock a spring-bolt, R, adapted, when free, to automatically lock the table, all substantially in the manner and for the purpose herein set forth.

4. In a bottling-machine, the combination, with its master-shaft J⁴ and its intermittently-rotating table F, bottle-receptacles G G, and movable cases G', of the reciprocating plunger L, actuated by the weight L³ and by cam L⁵ on said shaft, substantially in the manner and for the purpose herein set forth.

5. In a bottling-machine, the combination, with its filling-cylinder, sirup-gage, and supply-valve, and with a master shaft actuating an intermittently-rotating table adapted to carry the bottles beneath the filling-cylinder, of a cam upon said master-shaft, actuating a pivoted lever coupled at its free end to the sirup-valve, so that the rotation of the shaft shall operate said valve in unison with the movement of the table, substantially in the manner and for the purpose herein set forth.

6. In a bottling-machine, the combination, with its filling-cylinder A and the master-shaft J⁴, actuating its intermittently-rotating table F, of a cam, P⁵, upon said shaft, actuating a pivoted lever, P⁴, coupled to a rack-bar, P³, geared by an interposed pinion, P², to a sliding bar, P¹, actuating a plunger, P, to produce a reciprocating movement of said plunger into and out of the upper end of the filling-cylinder, substantially in the manner and for the purpose herein set forth.

7. In a bottling machine, the combination, with the plunger P, rack-bars P¹ and P³, intermediate pinion, P², vibrating lever P⁴, actuating the rack-bar P³, and the cam P⁵, engaging said lever, of a second pivoted lever, P¹, coupled to the lever P⁴ in position to be engaged by a wiper, P⁶, upon the cam-shaft J⁴, all substantially in the manner and for the purpose herein set forth.

8. In a bottling-machine, the combination, with the cork-feeding tube N⁴, filling-cylinder A, and driving-plunger P, of the reciprocating jaws N N, interposed springs N² N², and converging ribs N³ N³, substantially in the manner and for the purpose herein set forth.

9. In a bottling-machine, the combination, with the sliding reciprocating jaws N N, reciprocating plunger P, intermittently rotating table F, and master-shaft J⁴, actuating the plunger and table, of a double cam, S⁴, upon said shaft, and a pivoted oscillating lever, S³, provided with a ring, S⁵, to encircle the cam, and coupled at its free end to a bell-crank fitted to engage and actuate the jaws, substantially in the manner and for the purpose herein set forth.

10. In a bottling-machine, the combination, with its cork-feeding tube and with its reciprocating plunger-bar for driving the corks, of a cork-receptacle fitted with a rotating bottom plate having a series of apertures therein adapted to pass successively over the upper end of the feeding-tube, and of a vibrating lever, n', actuated by the reciprocating movement of the plunger-bar, and made to engage a ratchet connected with the rotating bottom plate of the cork-receptacle, to produce by its movement an intermittent rotation of said plate at each movement of the plunger-bar, substantially in the manner and for the purpose herein set forth.

11. The combination, in a bottling-machine, with its feeding-tubes and valves and its filling-cylinder, and with a cam-shaft, J⁴, driven by a prime motor, of the intermittently-rotating bottle table or carrier F, a series of reciprocating bottle-cases, G' G', adapted to move up and down in said table, a reciprocating plunger, L, driven mediate by the cam-shaft, and adapted by its movement to force up the bottle-cases when they are brought into line with the filling-cylinder, a locking device, R, adapted to lock the table when the plunger is moving a bottle-case, and which is unlocked mediate by the rotation of the cam-shaft, to allow the proper movement of the table, a cork-supply tube, N⁴, reciprocating jaws N N, sliding under said tube and over the filling-cylinder and actuated by the cam-shaft, a plunger, P, reciprocating to and from the filling-cylinder to carry the corks into the same, and driven mediate by the cam-shaft, and a cork-receptacle, N⁵, provided with a rotating bottom actuated by the plunger-bar P', and provided with delivery-apertures registering with the cork-tube N, all substantially in the manner and for the purpose herein set forth.

In testimony whereof I have signed my name to this specification in the presence of two subscribing witnesses.
